UNITED STATES PATENT OFFICE.

CHARLES VAN DYKE HILL, OF ST. LOUIS, MISSOURI.

ELECTRICAL HEATER FOR HOT-WATER BAGS.

No. 861,851.

Specification of Letters Patent.

Patented July 30, 1907.

Application filed September 15, 1906. Serial No. 334,701.

To all whom it may concern:

Be it known that I, CHARLES VAN DYKE HILL, a citizen of the United States of America, residing in the city of St. Louis, in the State of Missouri, have invented 5 certain new and useful Improvements in Electrical Heaters for Hot-Water Bags, of which the following is a full, clear, and exact description, reference being had to the accompanying drawing, forming part of this specification.

10 My invention relates to an electrical heater for use in hot water bags for the purpose of heating the water therein or maintaining the water in a heated condition after it has been heated and introduced into the bags, the invention having for its object to provide an extremely simple and efficient heater in which a core member for the resistance wire is dispensed with, the resistance wire being introduced loosely into a receiving shell and being surrounded by heat absorbing and radiating material that is packed around the resistance 20 wire within the receiving shell.

Figure I is a side elevation of a hot water bag partly broken out and my electrical heater in position in said bag. Fig. II is an enlarged longitudinal section taken through the upper end of the hot water bag, and the 25 electrical heater on line II-II, Fig. I. Fig. III is an enlarged cross section taken through the electrical heater shell, the insulated resistance wire and the packing therein.

A designates a hot water bag of ordinary type which 30 is provided with a mouth B and a neck C. Located in the neck of the bag is the usual threaded bushing D having an inturned annular flange E at its lower end that supports a gasket F.

G is a hollow threaded stopper that is seated in the 35 bushing D and is provided with a perforated cap H.

1 designates a shell that is closed at its lower end and open at its upper end, this shell being adapted to be seated in the hollow stopper G and seat against the lower side of the stopper cap H.

40 2 designates a resistance wire that is laid loosely in the shell 1, the said wire being insulated throughout its extent in any suitable manner, such for instance, as by the wrapping of silk thread thereon in order that all portions of the wire may be insulated from each 45 other with the object in view of preventing short circuiting of the electrical current passed through the wire. The resistance wire is preferably folded into folds of approximately uniform length before it is introduced into the shell 1.

50 3 designates packing that is introduced into the lower end of the shell 1 and also packed around the resistance wire from the bottom of the shell to a point near the upper end of said shell. This packing is of heat radiating substance, such for instance, as sand and 55 when it is introduced into the shell 1 it serves to re-

ceive the heat evolved from the resistance wire during the passage of an electrical current therethrough and to radiate said heat through the shell to the body of water in the water bag. The terminals of the resistance wire are connected to the terminals of cords 4 60 that may be connected in any suitable manner to an ordinary electric lamp socket or other device from which an electrical current is to be received and delivered to the resistance wire of the heater. The cords 4 are united by a knot 5 after being passed through perforations in the stopper cap H of the hot water bag and this knot is located within the open upper end of the heater shell 1, in order that it may serve to prevent the withdrawal of the terminals of the cords from said shell and avoid the subjection of the resistance wire 65 to strain or disruption if the cords exterior of the water bag are subjected to strain. For the purpose of firmly embedding the knotted portions of the cords in the heater shell, I introduce into the open upper end of the shell and above the packing therein a packing 70 75 of asbestos or other suitable material which is thoroughly tamped into the shell before said shell is introduced into the hollow stopper G.

The electrical heater herein described is of extremely simple and inexpensive construction and one in the use 80 of which a high degree of heating power with a minimum of expenditure of electrical energy may be established and maintained.

I claim:

1. In an electrical heater for hot water bags, the combination of a bag stopper, a shell having an open upper end and seated in said stopper, a resistance wire in said shell, and cords extending through said stopper and into said shell; said cords being united interior of said shell, substantially as set forth. 85

2. In an electrical heater for hot water bags, the combination of a bag stopper, a shell seated in said stopper and having an open upper end, a resistance wire loosely positioned in said shell, cords extending through said stopper and united interior of said shell and having connection 95 with said resistance wire, and a packing surrounding the united portions of said cords within said shell, substantially as set forth.

3. In an electrical heater for hot water bags, the combination of a bag stopper, a shell having an open upper end and seated in said stopper, a resistance wire in said shell, and cords extending through said stopper and into said shell; said cords being knotted together interior of said shell, substantially as set forth. 100

4. In an electrical heater for hot water bags, the combination of a bag stopper, a shell seated in said stopper and having an open upper end, a resistance wire loosely positioned in said shell, cords extending through said stopper and knotted interior of said shell and having connection with said resistance wire, and a packing surrounding the 110 knotted portions of said cords within said shell, substantially as set forth. 105

CHAS. VAN DYKE HILL.

In presence of—

NELLIE V. ALEXANDER,
BLANCIE HOGAN.
